Attorneys.

UNITED STATES PATENT OFFICE.

GEORGE E. STONEBURNER, OF DES MOINES, IOWA.

DESIGN FOR A DIAL.

SPECIFICATION forming part of Design No. 23,188, dated April 10, 1894.

Application filed February 9, 1894. Serial No. 499,687. Term of patent 3½ years.

To all whom it may concern:

Be it known that I, GEORGE E. STONEBURNER, a citizen of the United States of America, residing at Des Moines, in the county of Polk and State of Iowa, have invented and produced a new and original Design for a Dial, of which the following is a specification, reference being had to the accompanying drawing, in which—

10 A represents a dial.

At the circumference of the face of the dial there is a circle B and that circle is divided into a series of distinct spaces C and in those spaces playing cards are grouped to show the

15 different hands and characters known in playing the game of cards called "draw poker." Figures of persons, animals and other objects are also located in the said circle B for purposes of ornament and amusement.

In the center of the dial A is the figure of 20 a man holding cards in his hands.

What I claim is—

The design for a dial, substantially as shown and described.

GEORGE E. STONEBURNER.
